UNITED STATES PATENT OFFICE.

WILLIAM G. KENDALL, OF NEWARK, NEW JERSEY.

VANITY-CASE.

1,329,412.

Specification of Letters Patent. Patented Feb. 3, 1920.

Application filed March 19, 1918. Serial No. 223,421.

To all whom it may concern:

Be it known that I, WILLIAM G. KENDALL, a citizen of the United States, residing at Newark, in the county of Essex and State 5 of New Jersey, have invented certain new and useful Improvements in Vanity-Cases, of which the following is a specification.

This invention relates to vanity cases or similar containers for toilet articles such as 10 compressed powder and rouge tablets or the like and the primary object of the present invention is to provide a novel and efficient means for retaining the articles within the case.

15 It is a further object of the invention to provide in a container of the class mentioned, means for retaining the powder and rouge tablets in place, which means will be inconspicuous as a retaining means and will 20 at the same time enhance the artistic appearance of the article as a whole, the said retaining means furthermore having the appearance of a partition wall within the container serving to divide the interior of 25 the body of the container into separate compartments housing the rouge and powder tablets respectively.

A further object of the invention is to 30 provide within a container of the class mentioned means for retaining in place the articles disposed therein, which means will serve, as stated above, as a partition wall to divide the interior of the body of the container and also as a means for relatively 35 bracing the front and rear walls of the said body so that while such articles are ordinarily made from light sheet metal, the one embodying the invention will be exceptionally strong and not liable to have its walls 40 crushed in or otherwise distorted.

The invention has as a further object to provide a retaining means for the purpose stated which will securely hold the rouge and powder tablets or similar articles within 45 the container and will yet permit of ready removal of the bases or supports for the tablets after the tablets have been consumed and it is desired to place fresh tablets within the container, the retaining means further 50 presenting the advantage that when the new tablets are to be placed in position they are automatically locked in place when disposed within their respective compartments and pressed down into position upon the bottom 55 of the container. Thus not only may a lady making use of the vanity box readily re-

plenish the same whenever she so desires, but also the filling of the box in the factory may be accomplished in an expeditious manner and with little likelihood of injury to 60 the tablets.

As above stated the retaining means embodying the present invention is designed secondarily to serve as a partition wall dividing the interior of the container into separate compartments in which the rouge and powder tablets or cakes may be respectively housed, and a further feature of the invention resides in so forming this retaining member that in serving the purpose of a 70 partition wall, it will prevent the powder puffs which are disposed within the compartments coming in contact with each other so that there is no likelihood of powder from the rouge puff being deposited onto the face 75 powder puff, the said member therefore serving as a means for separating the two puffs.

So far as the fundamental principles of the invention are concerned, the invention 80 contemplates the provision between the articles to be retained, of a normally expanded means which is interposed between the articles and acts against the same to hold the articles firmly against relatively fixed ele 85 ments which in the illustrated embodiment of the invention are the opposite end walls of the body of the container, the said normally expanded means being capable of compression so as to permit of disengagement 90 and removal of either or both of the articles.

In the accompanying drawings:

Figure 1 is a perspective view of a vanity case embodying the present invention;

Fig. 2 is a vertical longitudinal sectional 95 view therethrough, the rouge and powder tablets and their respective puffs being shown in elevation;

Fig. 3 is a vertical transverse sectional 100 view on the line 3—3 of Fig. 2;

Fig. 4 is a perspective view of the retaining member removed from the case.

In the illustrated embodiment of the invention, the retaining device constitutes a part of a vanity case and serves to hold 105 within the case compressed tablets or cakes of rouge and face powder. However, this is to be considered as only one example of the many uses to which the retaining device may be put for it is not essential that the 110 articles to be retained be in the nature of powder tablets, nor is the device limited to

use in connection with but two of such articles for it might be employed in retaining a single article within a case, or one or several of the retaining devices might be employed in retaining more than two of the articles in place. It is also to be understood that I am not to be limited to the use of the specific retaining means illustrated in the drawings and to be hereinafter described, 5 inasmuch as normally expanded retaining members of many other forms could be employed for accomplishing the desired result.

In the drawings there is illustrated a vanity case preferably formed of light sheet metal and including a body indicated in general by the numeral 1 and a lid indicated in general by the numeral 2. The lid 2 is hinged as at 3 to the rear wall of the body 1 which wall is indicated by the numeral 4, 10 the said body further including a front wall 5, arcuate end walls 6, and a bottom 7. Of course, if desired the case may be of some shape other than that shown in the drawings, although it is preferable that the 15 case have the shape illustrated in the drawings. As is usual in articles of this class, the lid 2 is provided with a marginal depending flange 8 which is designed to fit down over the upper edges of the walls 4, 5 and 6 of the body and the said walls of the body have their upper marginal portions struck-in slightly, as indicated by the numeral 9, thus forming a narrow shoulder 10 within the body 1. Also as is usual in such 20 articles the front wall 5 is struck-out near its upper end to provide a protuberance 11 designed to snap into a similarly formed socket 12 in the forward side of the depending flange 8 of the lid 2 for the purpose of holding the lid in closed position and in the present instance the protuberance 11 is located 25 above the shoulder 10 and the purpose of thus relatively positioning the protuberance and shoulder will be presently explained.

As before stated, the articles to be held within the case constitute in the present instance a rouge tablet, indicated for example by the numeral 13, and a face powder tablet 14, and these tablets are compressed and 30 housed within shallow hollow bases 15 each of which has an annular upstanding wall 16 surrounding the respective tablet 13 or 14 as the case may be. While a powder tablet can best be maintained in whole condition 35 by the use of a shallow hollow base such as above referred to, and it is preferable to employ such a base where the retaining means of the present invention is to be made use of, nevertheless the retaining means will act 40 equally as well with such tablets when the same are merely secured upon flat disk-like bases. As before stated the end walls 6 of the body of the case are of arcuate form and their curvature corresponds to the marginal 45 contour of the tablets to be held so that

when the tablets 13 and 14 are disposed within the body of the case at the opposite ends thereof, the outwardly presented sides of the tablets will more or less snugly fit against the inner faces of the end walls 6 70 of the said body, the body being of such length as to provide sufficient space between the adjacent or inner sides of the tablet to accommodate the retaining member as will be presently explained.

The retaining member embodying the present invention is indicated in general by the numeral 17 and is preferably formed from an integral blank of resilient sheet metal of such contour and so stamped or otherwise fashioned as to provide sides 18 75 connected at their upper portions by a transversely rounded relatively narrow connecting portion 19, the said sides 18 being located in downwardly diverging planes as 80 clearly shown in Figs. 2 and 4 of the drawings. For a purpose to be presently pointed out each side 18 of the retaining member is provided with an integral outstanding flat and substantially horizontally 85 disposed flange 20 preferably of greater width at its ends than at its intermediate portion, the longitudinal edge of the flange being arcuate in form and inwardly curved as indicated by the numeral 21. Also for a 90 purpose to be presently stated each side portion 18 is stamped out to provide a protuberance 22 projecting from its outer face and located substantially midway between its 95 ends and at a point suitably spaced above 100 the lower edge of the respective side portion. By reference to Figs. 1 and 2 of the drawings it will be observed that the retaining device just described is to be positioned between the tablets 13 and 14 with the flanges 105 20 of its side portions 18 resting upon the upper face of the bottom 7 of the case, and by reference to Fig. 3 it will be observed that the retaining member is of a length substantially equal to the distance between the inner 110 faces, of the front and rear walls 4 and 5 of the body of the case so that when the said member is placed in position within the body its ends will abut against the said inner faces of the said front and rear walls 115 of the body and these walls will be therefore relatively braced and prevented from being crushed in or otherwise distorted. The height of the retaining member is such that when the member is preferably assembled within the body of the case one end of its connecting portion 19 will engage beneath the shoulder 10 at the front wall of the case and the other end of the connecting portion will engage beneath the hinge 120 125 lugs forming a part of the hinge 3, the said retaining member being in this manner securely held within the body although adapted to be removed upon slightly springing the walls 4 and 5 of the said body away 130

- from each other. In order to disengage the protuberance 11 from the socket 12 in the flange 8 of the lid 2 when it is desired to swing the lid to open position, it is necessary to exert 5 a slight inward pressure against the upper portion of the front wall of the box so as to slightly spring this portion of the said wall in an inward direction and while the retaining member extends between the front and 10 rear walls of the body and relatively braces these walls, nevertheless the stated inward springing of the upper portion of the front wall is not prevented because of the fact that the retaining member is of such height 15 as to stop short of the protuberance 11. As stated before the retaining member is formed from resilient sheet metal and therefore inasmuch as its side portions 18 are normally spaced apart and diverge in a down- 20 ward direction, the member may be considered as normally expanded. However, due to the resiliency of the member and particularly its connecting portion 19, the said member may be laterally compressed by 25 springing the side portions 18 toward each other. Therefore having positioned the retaining member substantially midway between the ends of the body of the case and also having disposed in position one of the 30 compressed powder tablets, the other tablet may be readily fitted and locked into place by merely disposing it within its respective compartment and exerting downward pressure against it tending to force it to position 35 resting upon the upper face of the bottom of the body of the case. As the tablet is thus forced downwardly, the upstanding wall of its base 15 will ride over the respective protuberance 22 forcing the side portions 18 together until the base has assumed a position 40 resting upon the upper face of the respective flange 20 whereupon the protuberance 22 will engage with the upper edge of the wall 16 and serve to lock said base and the 45 tablet carried thereby in place. Of course, when the tablet to be last disposed within the case has been fitted into place in the manner above described, the tablet which was first placed in position will be similarly locked against displacement and it will 50 be understood that when both of the tablets are properly positioned the expansion of the retaining member will result in its side portions 18 exerting lateral pressure against 55 the tablets or their bases causing the same to bear firmly against the respective end walls 6 of the body of the case so that the tablets will be additionally held in place through frictional contact with the said end walls of 60 the case body. When it is desired to remove either or both of the tablets to replenish the vanity case, either tablet may be tilted upwardly at its outer side, or in other words, its side which engages the respective end 65 wall 6 of the case body, or the forefinger and thumb of each hand may be caused to exert compressive force against the side portions 18 of the retaining member, thereby laterally compressing this member and permitting of the member being lifted upwardly 70 carrying with it the inner or adjacent sides of the tablets.
- It will be evident as before stated and particularly by reference to Figs. 1 and 2 of the drawings that the retaining member 75 serves also as a partition dividing the interior of the case body into two compartments each housing a respective one of the compressed powder cakes or tablets and each also housing a powder puff designed 80 for use in connection with the powder cake contained in that respective compartment, the said puffs being indicated in the drawings by the numeral 23.
- In certain of the claims which are to follow I will refer to a fixed element located within the container. As before stated the device of the present invention is capable of employment in securing in place a single one of the articles provided it is disposed 85 between the said article and a relatively fixed element, and inasmuch as either of the articles illustrated in the drawings may be considered as a fixed element located within the container, one of said articles 90 might be replaced by a wall of the container.
- Having thus described the invention, what is claimed as new is:
1. A device for the purpose stated comprising a member having side portions and a resilient connecting portion, the side portions being normally relatively expanded, and each side portion being provided inwardly of its margin with a protuberance. 100
  2. A device for the purpose stated comprising a member having side portions and a resilient connecting portion, the side portions being normally relatively expanded, each side portion being provided with a 105 protuberance, and base portions projecting outwardly from the lower edges of the side portions.
  3. The combination with an article container having opposite rigid walls and articles disposed within the container, of means for retaining the said articles in place comprising a member disposed between the articles and comprising resiliently connected side portions exerting pressure against the 115 articles and holding them against the said opposite walls of the container, and locking elements upon the said side portions for coöperation with the said articles.
  4. The combination with an article container a wall of which is provided upon its inner side with a shoulder, of a partition disposed within the container and having a portion engaged by the shoulder whereby to be retained against accidental displace- 125

- ment, the said member embodying means for exerting pressure against an article disposed beside the same in the direction of one of the walls of the container.
5. The combination with an article container a wall of which is provided upon its inner side with a shoulder, of a partition disposed within the container and having a portion engaged by the shoulder whereby 10 to be retained against accidental displacement, the said member embodying means for exerting pressure against an article disposed beside the same in the direction of one of the walls of the container, a lid hing- 15 edly connected with a wall of the container and coacting locking elements upon the lid
- and the first-mentioned wall of the container, the said first-mentioned wall of the container being inwardly yieldable at a point above the said shoulder thereon to 20 provide for disengagement of the said locking elements.
6. A device for the purpose stated comprising a member having side portions, a resilient connecting portion, and base por- 25 tions extending laterally from the lower edge of the side portions, each side portion being provided between the base and the connecting portion with a projecting lock- 30 ing element.

In testimony whereof I affix my signature.
WILLIAM G. KENDALL. [L. S.]
